PROCESS OF CRACKING HYDROCARBONS

Filed Dec. 21, 1925

UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING HYDROCARBONS

Application filed December 21, 1925. Serial No. 76,636.

This invention relates to improvements in process of cracking hydrocarbons, and in general refers to a process in which the oil after having been subjected to cracking conditions 5 of temperature and pressure so as to substantially vaporize the oil, the vapors are further superheated under cracking conditions of pressure to produce a substantial yield of aromatic hydrocarbons therefrom, and so 10 called fixed gases high in their content of unsaturated hydrocarbons.

One purpose to which the invention may be put, is the manufacture of such hydrocarbon gases as ethylenes, propylenes, butylenes, amylenes, and the like. The invention 15 is also adapted for the production of normally liquid aromatic hydrocarbons such as benzol, toluol, xylols, mesitylene, and the higher boiling point aromatic hydrocarbons.

20 Aromatics of the above character are now commercially produced very largely from the distillation of coal, but it is the essence of the present invention to produce them from the cracking of petroleum oil, in a more 25 practical and efficient manner than heretofore attempted.

In order to more clearly understand the invention, I have shown the accompanying drawing, which is a more or less diagrammatic side elevational view of an apparatus 30 in which the invention may be carried out.

Referring to the drawing, 1 designates a furnace in which is mounted the heating tube 2 connected at its inlet side to the raw oil 35 pump 3, and at its outlet side through the transfer line 4 having throttle valve 5 to an enlarged expansion tank or chamber 6. This tank or chamber may be provided with a residuum drawoff 7 controlled by throttle 40 valve 8 and with vapor outlet line 9 controlled by throttle valve 10. The vapor pipe 9 is in turn connected to a second heating tube 12 located in the furnace 13. The delivery end of this coil is connected through transfer line 14 to a second expansion chamber 15 which may, if desired, be mounted in a suitable setting 16. The chamber 15 may be provided with residuum drawoff 17 controlled by throttle valve 18 and with vapor 50 pipe 19 having throttle valve 20 leading into

the lower end of the dephlegmator 21. The arrangement is such that vapors can pass into the dephlegmator, but the reflux condensate cannot fall down through the pipe 19 into the chamber 15. The dephlegmator may be 55 provided with a plurality of baffles 22 and vapor outlet pipe 23 having throttle valve 24, which pipe 23 leads to the water condenser 25 and thence to receiver 26 between which is interposed throttle valve 27. The receiver 26 is equipped with gas outlet pipe 28 controlled by throttle valve 29. The pipe 28 may be connected with suitable gas holder 60 not shown. The receiver 26 is also equipped with liquid drawoff pipe 30 controlled by 65 throttle valve 31.

The reflux condensate from the lower portion of the dephlegmator 21 is drawn off through the pipe 32 in which is preferably 70 interposed a pump 33 having at either side thereof throttle valves 34 and 35. The reflux condensate may be pumped from line 32 through the extension 36 to the vapor pipe 9, or by closing the throttle valve 37 and opening the throttle valve 38 in the branch 40 the 75 reflux condensate may be delivered to storage or elsewhere, as desired.

However, in carrying out my invention, I find it will be advantageous in some cases at least, to return the reflux condensate to the line 9 where it is mixed with the vapors in 80 said line.

The raw oil in a preheated condition, may be fed from storage tank 41 by means of pump 42 and pipe 43 to the closed coil 44 seated in the dephlegmator, and thence through pipe 45 to the raw oil pump 3. If desired, the oil may be partially or wholly by-passed through the line 46 and throttle valve 47. In the event the line 46 is used, the valve 48 in the line 45 may be wholly or partially closed. A check valve 49 is interposed in the line 36, and so positioned that it only opens towards the line 9 thus permitting the reflux to run from the line 36 to the line 9. 95

By means of the apparatus shown, various differential pressures may be maintained on the system. Also various temperatures may be maintained on the system. The expansion tanks 6 and 15 may, if desired, be both in- 100

sulated, or may be externally and independently heated, the tank 6 being heated through a suitable furnace, not shown, if such heating is there desired.

5 One method of carrying out the invention may be described as follows:

Gas oil of 32° Baumé gravity from the Kansas field, may be fed through the heating coil 2 where it is heated to a transfer temperature of say 900° F. while under say 1000 pounds more or less pressure. The oil in a more or less liquid-vapor phase is passed to the expansion chamber 6, where it may be maintained at say 400 pounds pressure, more 10 or less, the vapors leaving the expansion chamber at say 875° F. The vapors pass from the line 9 into the heating coil 12 where they may be heated to a vapor temperature of say 1200° F. while subjected to a pressure of 15 200 pounds. If the reflux is mixed with the vapors before entering the coil 12, the reflux will likewise be vaporized and heated to such temperature at such pressure. The superheated vapors then pass through line 14 into 25 the expansion chamber 15 where the pressure may be at 150 pounds through suitably controlled reducing valve 14'. The vapors pass out through the vapor outlet 19 into the dephlegmator 21 where the heavier portions 30 thereof are condensed and drawn out of the dephlegmator and either sent to storage as for example, the storage tank 41 or they may be mixed with the vapors in the pipe 9. If desired, only a portion of the reflux condensate 35 is passed to the pipe 9 while the other portion is drawn off elsewhere. This will permit of controlling the relative proportion of reflux to the vapors in the pipe 9. The temperature of the dephlegmator may be so controlled either by the closed coil 44 herein described, or in any other suitable manner now well known in the art, so that they will leave the top of the dephlegmator at say 400° F., and thence pass into the water condenser 40 45 50 55 60 65 70 75 80 85 90 95 100 105 110 115 120 125 130

in which I treat and superheat the vapors after they have left the first expansion chamber shown in the drawing.

Aromatic compounds produced in the manner heretofore described, are highly desirable for use in the so-called anti-knock motor fuels. It is well known to those skilled in the art that aromatic hydrocarbons are better anti-knock motor fuels than paraffine hydrocarbons. Furthermore, by means of this process not only is a high percentage of aromatic hydrocarbons formed, but also a much larger percentage of olefines and also diolefines. It is also well known, that these olefine hydrocarbons are highly desirable as anti-knock motor fuels.

I claim as my invention:

1. A continuous process for cracking hydrocarbons, comprising initially raising a hydrocarbon oil to a cracking temperature while under a superatmospheric pressure, removing from the hydrocarbon oil such vapors as are evolved therefrom, raising the temperature of all of such vapors, prior to condensation, substantially 300° F., above the temperature to which said hydrocarbon oil was initially subjected, thereafter subjecting such vapors to reflux condensation and uniting reflux condensate separated from the vapors with the vaporous constituents being evolved from said hydrocarbon oil without returning said reflux condensate to the oil from which the vapors are evolved.

2. A process for cracking hydrocarbon oil, comprising initially heating the oil to a cracking temperature under superatmospheric pressure, thereafter permitting the oil to separate into vapors and a liquid residue, isolating the liquid residue from the process subsequently subjecting all of the separated vapors to a superheating treatment while under a superatmospheric pressure substantially lower than the pressure initially maintained on the oil, thereafter dephlegmating the vapors, to produce a substantial quantity of reflux condensate, and continuously uniting portions of the reflux condensate so produced with the vapors prior to their subjecting to said superheating treatment.

GUSTAV EGLOFF. 115

It is understood that it may be desirable in one method of operating the apparatus here shown, to accomplish certain desired results, to have the entire system under the same pressure of say 200 pounds more or less.

By carrying out the invention in the manner hereinbefore described, I convert a substantial part of the original charging stock into a relatively large percentage of fixed gases of the character hereinbefore described, and also into a relatively large percent of liquid aromatic hydrocarbons. This desirable result is obtained through the manner
